UNITED STATES PATENT OFFICE.

VICTOR PETIT, OF STRYJ, AUSTRIA-HUNGARY.

DEEP-BORING MACHINE.

SPECIFICATION forming part of Letters Patent No. 718,876, dated January 20, 1903.

Application filed July 30, 1901. Serial No. 70,209. (No model.)

To all whom it may concern:

Be it known that I, VICTOR PETIT, managing director, a subject of the King of the Belgians, residing in Stryj, Galicia, Austria-Hungary, have invented Improvements in Deep-Boring Machines; and I do hereby declare the following to be a full, clear, and exact description of the invention, such as will enable others skilled in the art to which it appertains to make and use the same, reference being had to the accompanying drawings, and to numerals of reference marked thereon, which form a part of this specification.

The object of this invention is to provide a deep-boring machine in which the drum from which the boring-rod is suspended by means of a chain either only revolves for the purpose of lowering the boring-rods into the bore-hole or for drawing them up out of the same or only performs an up-and-down motion (eccentric motion) to effect the small movements required by the punching-hammer.

Further, the improvements relate to a coupling for the driving-shaft to connect it to the drum, so that the latter can either raise or lower the bore-rod or effect the striking and falling motion for the punching-hammer. Finally, the improvements relate to balancing the bore-rod.

These improvements are illustrated in the accompanying drawings, in which—

Figure 1 is a front elevation of the boring-machine with its stand. Fig. 2 is a side elevation of the same. Fig. 3 is a plan of the machine, to a larger scale, without the framework and bore-rod; and Fig. 4, also to a larger scale, is a part section through the elements which are mounted on the shaft. Fig. 5 is an end elevation of Fig. 4. Fig. 6 is a section at A A in Fig. 3. Fig. 7 is a view of part of the deep-boring machine with a modification of the arrangement for balancing the bore-rod. Fig. 8 is a side elevation of Fig. 7, partly in section. Fig. 9 is a section at B B in Fig. 7. Fig. 10 is a sectional view on the line C C in Fig. 4.

A shaft 4 is mounted in the bearings 2 and 3, Fig. 3, of the cast-iron frame 1, on which the driving-wheel 5, Fig. 1, which may be a belt, chain, or wire-rope pulley, as desired, is keyed. Over part of the shaft 4 a sleeve 6 is

pushed, Fig. 4, one end of which is formed by a cylindrical disk 7. The shaft-sleeve 6 is provided with two equal eccentric disks 8 9, 55 Fig. 4, and its left end is made square. Two oppositely-set eccentric disks 10 11, which are connected together, are slid onto this square part, which, by means of the lever 13, mounted to pivot in a projection 15 of the frame and 60 engaging in a groove 12, can be traversed on the shaft-sleeve 6. On the eccentric rings 11, 8, and 9 is mounted the drum 17, which is thickened up at its center, as at 16, Fig. 4, and whose bore is also eccentric to correspond 65 with the eccentric rings 11, 8, and 9, so that the cylinder-drum is concentric with the shaft 4. A double wheel is mounted loosely on the thickened part 16 of the drum, the left half of which forms a worm-wheel 18, while the 70 right half is a chain-wheel 19. (See Figs. 1 and 8.) On both sides of the double wheel frames 20 and 21, which also loosely embrace the drum, are situated. In this latter is mounted the shaft of a double wheel 22 23, 75 similar to and above the double wheel 18 19 and preferably touching or gearing with the latter. A worm 24, journaled in the two transverse ties 25 26, connecting the frames 20 21, is situated between these two worm-wheels and is operated by the hand-wheel 27. This worm gears with both the worm-wheels. The chain 28 is led between both the chain-wheels, so that it is firmly gripped by the latter, and runs over the sheave 29 at the top of the 85 framing 30. (See Figs. 1 and 2.) These side frames 20 21 are provided with downwardly-projecting arms 31, which by means of a cross-piece carry the draw-rod 32, which in its turn carries the counterweight 33, composed of separate plates put on the draw-rod and held between the two lock-nuts 34 35. The draw-rod 32 is prevented from swinging by means of the fixed guide-ring 36. The smooth part of the draw-rod is connected to 90 the screwed part 37 by a nut 39, which is formed as a hand-wheel 38. The parts mounted on the thickened-up part of the drum are kept in position by two flange-rings 40 and 41. A rope 42, the ends of which are secured to the drum, runs over the rollers 43 and 44 at the head of the frame 30 and over a loose roller 45. This rope serves to raise the rod out of or to lower it into the bore-

hole, for which purpose it is secured to the roller 45.

In order to enable the eccentric disk 10 to be slid into the drum 17, the drum is bored 5 out concentrically for a corresponding distance from its left end. The square part at the left end of the shaft-sleeve 6 is separated from the round part by a collar 47.

The coupling for the deep-boring machine 10 is arranged as follows: The disk 48 is made in one piece with the drum 17 or connected rigidly to the same. An arm 49 is keyed onto the driving-shaft 4, this latter being independent of the disk 48. A brake-band 50, of 15 steel or the like, encircles the disk 48, which in certain cases may be lined with wood. One end 51 of this band is secured to the arm 49 by means of the pin 52, the other end 53 of the band being secured to a chain, rope 54, 20 or the like, which latter is led over a roller 55, mounted to turn on a pin 56, fixed in the arm. The end of the chain 54 or the like is connected to a lever 57, which pivots on a pin 58 in the arm 49. The lever 57 is coupled to a 25 collar 60 on the shaft 4 by means of a link 59. A bifurcated L-lever 61 is mounted to pivot in a supporting-bracket 62. By pulling on a handle 63, provided on the lever 61, or by releasing the same the collar 60 is traversed longitudinally on the shaft 4 and imparts its motion to the lever 57, which tightens or loosens the chain 54, which in its turn causes the 30 brake-band 50 to be tightened or the reverse around the disk 48.

35 The action of the coupling is as follows: The shaft 4 is driven by any suitable means. The arm 49, keyed to this shaft, revolves with it. If now tension be put on the brake-band 50 around the disk 48 by means of the lever 40 61, the disk 48 will be caused to revolve too through the medium of the collar 60, link 59, lever 57, and chain 54, and through the friction of the brake-band. The greater the resistance offered by the disk 48 through the 45 medium of the arm 49 against rotation the more the brake-band 50 must be tightened. As soon as the tension in the brake-band ceases the disk 48 is released from the shaft 4—that is to say, the coupling is disengaged. 50 To reduce the wear of the disk caused by the brake-band, the disk 48 may be jacketed with wood.

It is desirable to provide a support 64 for holding the bracket 62 of the lever 61 in position. This support is bolted to the frame 55 of the machine. A collar 65, with set-screw, prevents the displacement of the bracket 62 on the shaft 4. A flat spring 66, secured at the end of the arm 48, holds the brake-band 60 in its off position and keeps it off the periphery of the disk 48.

In the position shown in Fig. 4 the drum 17 will only rise and fall when the shaft-sleeve and the eccentric disks 11, 8, and 9, which 65 are connected rigidly with it, revolve, and when the drum is prevented from turning by some external influence—for example, the

tension of the rope 42. As soon, however, as the eccentric disk 10 is forced into the concentric bore 46 by means of the lever 13, Fig. 70 3, the up-and-down motion of the drum can no longer take place, and the drum will now revolve with the shaft-sleeve 6. If the shaft-sleeve is to be taken along, all that is necessary is to engage the coupling by pulling the 75 handle 63, as described above. When the drum 17 has been started to revolve, as described, the rope 42 will roll up on the drum, and the roller 45, together with the bore-rod, which it carries in this case, is raised. By 80 releasing the handle 63 the drum 17 is uncoupled from the shaft 4, so that in consequence of the weight hanging from the sheave 45 the rope 42 is unwound from the drum, causing the latter to revolve and the sheave 85 45 to sink, the bore-rod being lowered thereby. For regulating the unwinding of the rope a suitable brake arrangement—e. g., a brake-band around the disk 7—may be provided. The lowering of the bore-rod into the 90 bore-hole has to go on till it touches or rather till the punching-hammer touches the bottom, thus reducing the weight on the sheave 45 to such an extent that there is only enough tension left on the rope to prevent 95 the drum revolving and allowing the up-and-down motion to commence. The bore-rod is now detached from the rope and secured to the chain. By means of the hand-wheel 27, the double wheels 18 22 19 23, and of the chain 100 28 the bore-rod is then raised above the ground and the lever 13 so set that the drum 17 is only raised and lowered and through the medium of the chain 28 imparts this up-and-down motion to the bore-rod and punching-hammer. When the punching-hammer has worked away the bottom to such an extent that it no longer strikes, the bore-rod is correspondingly lowered by means of the hand-wheel 27. The counterweight 33 can 105 be adjusted for different weights of bore-rod by adding or taking away some of the weight-slabs, so that the power required to raise the bore-rod is reduced to a minimum.

When the bore-rod is to be withdrawn from 115 the bore-hole, the drum 17 may be released from the counterweights 33 by lowering them by means of the hand-wheel 38 until they rest on the rigidly-fixed guide-ring 36 to avoid unnecessary friction.

Figs. 7 to 9 illustrate a modification of the bore-rod-counterbalancing arrangement, which consists, substantially, of the employment of springs in place of the counterweights, the springs being situated inside a drum. 125 Preferably these springs are arranged one above the other in several tiers. They act on a screw-spindle, which is suitably connected to the driving-shaft of the deep-boring machine. At the same time the normal tension 130 of the springs may be adjusted by means of a nut on the screw-spindle. By means of this arrangement part of the weight of the bore-rod is borne by the system of springs as the

bore-rod is lowered to lighten the work of raising the bore-rod, so that the power for driving the bore-machine is reduced to a minimum. Beneath the drum 17 a cylindrical drum-head 67 is secured to the frame of the machine 1 and is preferably provided with a movable bottom 68 and a fixed partition 69. Between this fixed partition and the movable bottom are strong spiral springs 70, held in position by projections 71 on the bottom and on the partition. A screw-spindle 72 passes through the drum-head 67, the top end of which is pivoted to the side brackets 74 by means of a transverse pin 73, the brackets being suspended from the drum 17 of the boring-machine. A nut 75 is provided on the screw-spindle 72 and is made in the form of a hand-wheel 76, the nut forming the support for the lower bottom, the travel of the nut being limited by means of two nuts 77 78 for the purpose of adjusting the tension of the springs 70. The object of this arrangement is to store the work performed by the falling bore-rod in the springs and to use the tension of the same in the subsequent lifting of the bore-rod, and thus relieve the driving-motor. The action of the arrangement is as follows: When the eccentrics have reached the lowest position of their stroke—*i. e.*, when the bore-rod has been raised from the bottom of the bore-shaft a distance equal to the travel of these eccentrics—the tension of the springs is regulated to the weight of the bore-rod by means of the hand-wheel 76 and nuts 77 78. As the eccentrics now move upward, lowering the bore-rod into the bore-shaft, the spiral springs 70 are compressed by the pull caused by gravity, so that the work thus stored may be employed for aiding the subsequent upstroke of the bore-rod.

Having now particularly described and ascertained the nature of my said invention and in what manner the same is to be performed, I declare that what I claim is—

1. In a well-boring machine, the combination of the boring-tool, a vibratory structure, means for vibrating said structure, a flexible device carrying said tool at one end, and an adjusting means for said tool carried by said structure, said device being engaged with said adjusting means, substantially as described.

2. In a well-boring machine, the combination of the boring-tool, a vibratory structure, means for vibrating said structure, a flexible device carrying said tool at one end, coact-

ing rotary gripping members engaging said flexible device and mounted in said structure, and means for rotating said members, substantially as described.

3. In a well-boring machine, the combination of the boring-tool, a vibratory structure, means for vibrating said structure, a flexible device carrying said tool at one end, coacting rotary gripping members engaging said flexible device and mounted in said structure, worm-wheels formed one with each gripping member, and a worm engaging said worm-wheels, substantially as described.

4. In a well-boring machine, the combination of a rotary part formed with an eccentric portion, a sleeve receiving the eccentric portion of said rotary part, a vibratory structure receiving and sustained by said sleeve, a boring-tool, a flexible device carrying said tool at one end, and operative connecting means between said flexible device and the vibratory structure, substantially as described.

5. In a well-boring machine, the combination of a rotary part formed with an eccentric portion, a sleeve receiving the eccentric portion of said rotary part, means for temporarily locking said sleeve and rotary part together, a vibratory structure received and sustained by said sleeve, a boring-tool, a flexible device carrying said tool at one end, and operative connecting means between said flexible device and the vibratory structure, substantially as described.

6. In a well-boring machine, the combination of a rotary part formed with an eccentric portion, a sleeve receiving the eccentric portion of said rotary part, means for temporarily locking said sleeve and rotary part together, a vibratory structure received and sustained by said sleeve, a boring-tool, a flexible device, operative connecting means between said flexible device and the vibratory structure, and another flexible device secured to and adapted to wind on said sleeve, said flexible devices being adapted to be interchangeably connected to the boring-tool, substantially as described.

In testimony that I claim the foregoing I have hereunto set my hand this 15th day of July, 1901.

VICTOR PETIT.
